DESIGN FOR A MOUNTING FOR ARTICLE DISPLAY PURPOSES

Julius G. Hoeflich, Springfield, Ohio, assignor to
The Chaney Manufacturing Company, Springfield,
Ohio, a corporation of Ohio

Application August 29, 1933, Serial No. 49,161

Term of patent 7 years

To all whom it may concern:

Be it known, that I, JULIUS G. HOEFLICH, a citizen of the United States, residing at Springfield, Clark County, Ohio, have invented a new, original and ornamental Design for a Mounting for Article Display Purposes, of which the following is a specification, reference being had to the accompanying drawing forming a part hereof.

Fig. 1 is a perspective view of a mounting for

article display purposes embodying my new design. Fig. 2 is a front elevation thereof. Fig. 3 is a top plan view. Fig. 4 is a side elevation.

I claim:

The ornamental design for a mounting for article display purposes substantially as shown.

In testimony whereof I have hereunto set my hand this 24th day of August, 1933.

JULIUS G. HOEFLICH.
